EDWARD C. GRASSMANN, OF MAPLEWOOD, NEW JERSEY, ASSIGNOR TO HARRY C. SCHICK, INC., A CORPORATION OF NEW JERSEY

SAFETY CLASP

Application filed February 8, 1929. Serial No. 338,378.

This invention relates, generally, to improvements in safety clasps or fasteners for jewelry, such as necklaces, bracelets and similar articles.

The invention has for its principal object 5 to provide a novel safety clasp or fastener which is of exceedingly simple construction comprising but two separable and unitary elements, is neat in appearance, very easy to manipulate both when fastening and unfastening the same, and in which the separable elements have auxiliary guard means adapted to prevent complete separation of said elements should the same become accidentally 10 disengaged from their normal mutually interlocked relation.

The invention has for a further object to provide a clasp or fastener comprising separable male and female elements adapted to be 15 formed from unitary sheet metal stampings and having safety guard means which does not interfere with easy fastening or unfastening of the clasp as desired.

Other objects of this invention, not at this 20 time more particularly enumerated, will be clearly understood from the following detailed description of the same.

The invention is clearly illustrated in the accompanying drawings, in which:—

Fig. 1 is a top plan view of the novel jewelry clasp or fastener of this invention with the elements in normal interlocked relation;

Fig. 2 is a side view of the clasp illustrated in Fig. 1;

Fig. 3 is an end view of the clasp;

Fig. 4 is a bottom plan view of the clasp, in partial disengaged relation to the female element; the male element being shown.

Fig. 5 is a plan view of the flat stamping 40 from which the female element of the novel jewelry clasp is formed; and

Fig. 6 is a perspective view of the structure shown in Fig. 5 but with the spacing posts bent upwardly from the stamping preparatory to the final bending operation of the 45 same.

Similar characters of reference are employed in all of the hereinabove described views, to indicate corresponding parts.

Referring now to the said drawings, the

novel safety clasp or fastener comprises a unitary female element formed from a single flat stamping illustrated in Fig. 5. This stamping is so shaped as to provide a face or front plate 9, which is joined at one end by an end post 10 to a back plate section 11 and at the other end by an end post 12 to another back plate section 13. Back plate section 11 is provided at its free end with a wedge or key-stone shaped space or recess 14 which is adapted to cooperate with a similar wedge or key-stone shaped tenon or projection 15 formed on the free end of back plate section 13. A pair of oppositely arranged lugs or spacer posts 16 are provided at the side edges of back plate section 11 and a pair of similar spacer posts 17 are provided at the side edges of back plate section 13.

In folding the female stamping so as to form the female element, the spacer posts 16 and 17 are bent upwardly at right angles to the inner surface of the stamping, as illustrated in Fig. 6. The back plate sections 11 and 13 are then folded over into parallel superimposed relation to the front plate 9, 70 the metal of the end posts 10 and 12 yielding to permit this folding over operation. In folding over the back plate sections, the tenon 15 of section 13 is caused to enter the recess 14 of section 11. The free ends of the spacer posts 16 and 17 are moved into abutting relation with the inner surface of the front plate 9 during the folding over operation. These spacer posts serve to space the back plate sections at equal distances from the front plate, so that these back plate sections are in alignment and together form what in effect is a continuous back plate. During the folding over operation the end posts 10 and 12 are caused to assume a curvilinear shape as especially illustrated in Fig. 2.

Thus when the female element is completely formed, it comprises a unitary box-like structure having a front plate and a back plate arranged one over the other in parallel aligned relation and spaced apart by posts 16 and 17 to provide an intermediate space or chamber, the end posts 10 and 12 serving to secure the front and rear plates together. The end post 10 at the rear end of 90 95 100

the female element may have a link 18 secured thereto, to which link one end of a necklace, chain, bracelet or the like, may be connected, or any other suitable means may be employed for connecting such articles to the rear end of the female element.

The separable male element of the clasp or fastener comprises a substantially U-shaped member consisting of two laterally resilient arms 20 and 21 which are joined at their forward ends. Each arm is provided near the rearward or outer free end thereof with a notch or indentation 22 to cooperate with a post 17 near the front end of said female element. The free end portions of these arms are also provided with outwardly turned finger-pieces 23. Arm 21 is also provided with an eye-portion or ring 24 to receive the attachment of one end of the necklace, chain, bracelet or the like, to be served by the clasp or fastener.

As will be apparent from an inspection of Fig. 4 of the drawings, the male element can be assembled with or disassembled from the female element in only one manner. This manner is carried out by turning the male element so that its longitudinal axis extends substantially at right angles to the longitudinal axis of the female element. The male element can then be moved either so that the post 12 passes into or out of the space between the arms 20 and 21 of the male element as desired.

Thus, in operation, assuming that it is desired to fasten the clasp, the male element is turned at right angles to the female element and the male element is then manipulated so that the free end portion of the arm 20 enters the space within the female element extending between end post 12 and spacer posts 17. The male element may then be moved so as to be in longitudinal alignment with the female element in which position the end post 12 is between the arms 20 and 21 and adjacent the junction of these arms as illustrated in Fig. 4. The male element may then be thrust or moved directly into the female element. The continued inward movement of the male element carries the resilient arms 20 and 21 into engagement with the posts 17 adjacent the outer end of the female element, the notches or indentations 22 thereof arrive opposite said posts 17, whereupon the tension to which said arms 20 and 21 are subjected causes the same to spring laterally outward to thereupon engage said notches or indentations 22 with said posts 17, thus interlocking the male element with the female element to hold the former against withdrawal from the latter. If by any chance, the notches or indentations 22 should become accidentally disengaged from the posts 17, so that the male element is freed for outward withdrawal, the outward movement of said male element would carry the junc-

ture of arms 20 and 21 into abutting engagement with end post 12, whereupon the latter arrests further outward movement of the male element and thereby preventing complete separation of the same from the female element. If it is desired to separate the male element from the female element, the former must be turned at right angles with respect to the latter and then moved until end post 12 leaves the space between arms 20 and 21. This compound movement could not occur accidentally, since the tension of the necklace or other article served by the clasp would retain the male and female elements in substantially longitudinal alignment.

It will be noted that the male element provides for a double grip or interlock with opposite posts 17 of the female element since the outer sides of each of the notched arms 20 and 21 engages one of these posts, the male member or element as a whole is firmly held against lateral canting or shifting, thus reducing the likelihood of accidental separation of the notched arms 20 and 21 from operative interlocked engagement with said posts 17.

It will be noted that the dove tail interlocking of the back plate sections gives the female element great strength not only in a longitudinal but also in a transverse direction, making it impossible for these sections to have relative movement in their common plane.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. In a device of the kind described, a female member formed from a flat unitary stamping, said member comprising a front plate, end posts formed on the end of said front plate and extending rearwardly thereof, a back plate arranged in spaced parallel relation to said front plate, said back plate consisting of sections having portions in mutual interlocking relation, each of said sections being formed integral with one of said end posts, spacer posts formed on said back plate sections and having their free ends abutting said front plate.

2. In a device of the kind described, a female member formed from a flat unitary stamping, said member comprising a front plate, end posts formed on the ends of said front plate and extending rearwardly thereof, a back plate arranged in spaced parallel relation to said front plate, said back plate consisting of sections having portions in mutual interlocking relation, each of said sections being formed integral with one of said end

posts, spacer posts formed on said back plate sections and having their free ends abutting said front plate, and a male element adapted to extend into said female member in straddling relation to one of its end posts, said male element having portions capable of interlocking with certain of said spacer posts.

3. In a device of the kind described, a female member formed from a flat unitary stamping, said member comprising a front plate, end posts formed at each end of said front plate and extending rearwardly thereof, a back plate consisting of two sections, each of said sections being an enlarged continuation of one of said end posts, one of said sections having a key-stone shaped recess and the other of said sections having a key-stone shaped projection conforming to said recess in said first section to thereby unite said sections together in longitudinal abutting relation, spacer posts formed on the marginal edges of said sections and projecting forwardly into abutting relation with the marginal edges of said front plate to thereby space said front and back plates in parallel relation, and a male element adapted to extend into said female member, said male element having resilient arms to embrace an end post, and said arms having notches for interlocking with the spacer post of one of said back plate sections.

In testimony, that I claim the invention set forth above I have hereunto set my hand this 31st day of January, 1929.

EDWARD C. GRASSMANN.
